UNITED STATES PATENT OFFICE.

GEORGE S. EVERHART, OF OSHKOSH, WISCONSIN.

DRIVE-CALK FOR HORSESHOES.

1,274,025.

Specification of Letters Patent. Patented July 30, 1918.

Application filed April 8, 1916. Serial No. 89,765.

To all whom it may concern:

Be it known that I, GEORGE S. EVERHART, a citizen of the United States, residing at Oshkosh, county of Winnebago, and State of 5 Wisconsin, have invented new and useful Improvements in Drive-Calks for Horseshoes, of which the following is a specification.

My invention relates to improvements in 10 drive calks for horseshoes and pertains especially to the toe calks.

Heretofore, a common practice has been to drive a pair of ordinary calks into sockets formed in the toe of the shoe, each of said 15 calks having a blade similar to the blade of a heel calk and only a little wider than the shank. These calks frequently prove inadequate in soft ice or ground through which they tend to strip when the horse is pulling 20 a heavy load. Also they tend to rotate and frequently do rotate upon the shank axes, whereby the blades are shifted from a normal position, transverse to the shoe, to various angular positions in which they furnish an unstable support, frequently causing 25 the horse to stumble and in some instances producing severe injuries.

The object of my invention is to provide means whereby a single toe calk, having an 30 elongated blade, may be securely anchored to a shoe by a pair of shanks. A further object of my invention is to provide means whereby a pair of shanks connected with a single calk blade, may be anchored in the 35 ordinary sockets, notwithstanding the fact that the axes of the sockets may not register exactly with the axes of the shanks. It is not possible to make horseshoes in which the sockets will be exactly located or definitely 40 spaced to receive a plurality of shanks carried by a single calk, since each horseshoe requires fitting to the hoof preparatory to attaching it and inserting the calks. My invention, therefore, contemplates the use of 45 eccentrically formed socket bushings, which may be rotated to any desired position preparatory to inserting the calk shanks and which are contractible upon the shanks when the latter are driven into position.

50 In the drawings:

Figure 1 is a view of the under side of a horseshoe showing my improved toe calk in position for use.

Fig. 2 is a fragmentary view of the toe 55 portion of the shoe, as seen from the under side, the toe calk being removed and one

portion of the shoe, including one of the anchor sockets and bushings, being illustrated in horizontal section, drawn generally on line 2—2 of Fig. 3. 60

Fig. 3 is a vertical sectional view drawn on line 3—3 of Fig. 1.

Fig. 4 is a perspective view of my improved toe calk detached.

Like parts are identified by the same reference characters throughout the several views.

A horseshoe A may be of any ordinary construction, in which drive sockets are provided on the toe portion. The shoe illustrated is provided with heel calks B of the 70 drive-calk type, these also being of ordinary construction. The specific type of heel calk is non-essential. The toe of the shoe is provided with a pair of shank-receiving apertures or sockets C, which may be of ordinary 75 type and are preferably made a little larger than the ordinary calk shank. The walls of these sockets or apertures C are lined with split bushings D, the lower ends of which are provided with outwardly projecting 80 flanges D' to facilitate removing the bushings and the calks therein. The walls of these bushings are preferably slightly tapered upwardly to their upper ends d, (at least along their outer surfaces,) and they 85 are also thickened progressively from the vertically extending slit d' to the opposite side d'', whereby the aperture, of which the bushing forms the wall, is eccentrically located with reference to the aperture or 90 socket C in the shoe. Normally the edges of the bushings are slightly separated at the slits d', whereby, when the bushings are driven into the sockets C, their walls are 95 pressed inwardly, thereby contracting the opening E and bringing the edges nearer together at the slits d''.

The toe calk blade F is long enough to extend entirely across both of the apertures C formed in the toe of the shoe, the ends 100 of the blade F preferably projecting beyond these apertures on each side. The portion of the blade nearest the shoe may be abruptly thickened on the rear side, thereby providing a reinforcing flange F'. This 105 feature will be used principally, however, for the sharp calks. From this blade, a pair of shanks G extend upwardly. These shanks are spaced apart approximately at the same distance from each other as the 110 sockets C in the toe of the shoe. They may also, if desired, be slightly tapered upwardly

and their diameter is such that when the shanks are inserted into the bushings D and driven with the bushings into the shoe sockets, the bushings will contract upon the 5 shanks and anchor them rigidly in position.

Preparatory to driving in the toe calk shanks G, the bushings will be rotatively adjusted until they are in a position to enter the sockets. They are preferably first placed 10 upon the shanks, and then rotated, while the shanks and bushings are being adjusted to the sockets. Therefore, the apertures E will provide sockets in which the shanks may be accurately seated, without cramping 15 or binding against one wall or side of the aperture, more than against another wall or side thereof. Also, both bushings and shanks may be driven in simultaneously and far enough to be securely anchored in the 20 shoe sockets C, whereupon each shank G will reinforce the other and the calk blade F will be held rigidly in a true transverse position. The flanges D' need not bear upon the shank but the bushings and sockets may 25 be so formed that the bushings will be contracted on the shanks and wedged into the sockets tightly before the flanges D' reach the shoe. I am, therefore, enabled to provide a driven toe calk having the form and 30 all the advantages of a welded calk with the additional advantage that my improved toe calk may be extracted from the shoe and replaced at pleasure or other toe calks substituted without removing the shoe from the 35 hoof of the horse.

While I have described the shanks G of my improved toe calk, as possibly having a slight upward taper, it is obvious that this is not essential. If the outer surface of the 40 bushing D and also the wall of the socket C are slightly tapered, a bushing which fits the socket and also the shank, may be wedged in between the shank and the socket wall by driving in the shank and bushing, 45 even though the shank may be cylindrical in form.

The form of the calk blade is immaterial and may be changed at pleasure to suit the requirements of the road, or of changing 50 seasons.

I claim:—

1. A horseshoe provided with a set of toe sockets, bushings seated in said sockets, and a toe calk having a plurality of shanks 55 anchored in said sockets with the bushings interposed between the shanks and the socket walls, said bushings being split and having shank-receiving apertures eccentric to the sockets in which the bushings are seated,

whereby the bushings may be rotatively ad- 60 justed upon the shanks, to properly enter the sockets preparatory to driving the shanks and bushings into the sockets.

2. A horseshoe provided with a set of calk-receiving sockets, a calk having a plu- 65 rality of shanks adapted to enter said sockets, and anchor members adjustably mounted in said sockets and adapted in different adjustments to vary the position of the shanks therein, said anchor members being 70 also adapted to serve as wedges to rigidly hold the shanks in the sockets.

3. A toe calk having an elongated blade provided with a reinforcing flange along its upper margin and also having a set of 75 shanks connected with the upper margin of said blade, in combination with a shoe provided with a set of toe sockets adapted to receive said shanks and a set of eccentric contractible bushings adapted to be inter- 80 posed between the shanks and the socket walls, said bushings being rotatably adjustable to facilitate the insertion of the shanks.

4. A horseshoe provided with a calk-re- 85 ceiving socket, a calk having a shank seated in said socket, and a split bushing interposed between the calk shank and the wall of the socket, said bushing being thicker upon one side than upon the other.

5. A toe calk having an elongated blade 90 provided, near each end, with an upwardly projecting shank, in combination with a set of split bushings adapted to embrace said shanks, said bushings having shank-receiving 95 apertures eccentric to their outer surfaces.

6. A toe calk having an elongated blade provided, near each end, with an upwardly projecting shank, in combination with a set 100 of split bushings adapted to embrace said shanks, said bushings having shank-receiving apertures eccentric to their outer surfaces, and said bushings also having out- 105 wardly projecting annular flanges at their lower ends.

7. A horseshoe provided with a set of toe 110 sockets, in combination with a toe calk hav- ing a plurality of shanks adapted to enter said sockets respectively, and means for anchoring the shanks in the sockets with the axes of the shanks eccentric to the axes of the sockets.

In testimony whereof I affix my signature in the presence of two witnesses.

GEORGE S. EVERHART.
